UNITED STATES PATENT OFFICE.

ALEXANDER LINK, OF ST. PAUL, MINNESOTA.

PLANE.

No. 902,974.

Specification of Letters Patent.

Patented Nov. 3, 1903.

Application filed September 11, 1907. Serial No. 392,324.

To all whom it may concern:

Be it known that I, ALEXANDER LINK, a citizen of the United States, and a resident of St. Paul, in the county of Ramsey and State of Minnesota, have invented a new and Improved Plane, of which the following is a full, clear, and exact description.

This invention relates to planes, and more particularly to that class of planes known as router planes.

An object of the invention is to provide a simple, strong and efficient plane for cutting grooves or rectangular cavities and having means for easily and rapidly adjusting the cutter.

A further object of the invention is to provide a device of the class described having handles by means of which it can be manually operated, and having a cutter adapted to be projected from the plane stock, one of said handles controlling the cutter and serving both to operate the plane and to adjust the cutter.

The invention consists in the construction and combination of parts to be more fully described hereinafter and particularly set forth in the claims.

Reference is to be had to the accompanying drawings forming a part of this specification, in which similar characters of reference indicate corresponding parts in all the views, and in which

Figure 1 is a plan view of my plane, showing the same in position to cut a groove in a plank; Fig. 2 is a section on the line 2--2 of Fig. 1; Fig. 3 is a section on the lines 3--3 of Figs. 1 and 2; Fig. 4 is a section on the line 4--4 of Fig. 2, showing parts broken away.

Before proceeding to a more detailed explanation of my invention, it should be understood that the plane can be used for the usual purposes to which a router plane is applicable, for instance, the cutting away of material between saw cuts to form a groove, or the forming of rectangular cavities in wood and the like; for this purpose I provide a plane stock having two handles by means of which it can be manually operated. The plane stock has a cutter which can be projected from the sole of the stock and which is removably mounted so that it can be replaced by other cutters of different sizes. The cutter can be secured in a plurality of positions and is provided with a gage to insure the maintaining of the cutter at a uni-

form degree of projection from the stock. One of the handles of the plane is rigid, while the other is revoluble and is connected by means of a suitable intermediate gear 60 with the cutter, in such a way that by turning the movable handle in one direction or the other the cutter is projected from or withdrawn toward the stock.

Referring more particularly to the drawings, *i* represents the stock of the plane, which comprises preferably a flat plate or sole of any suitable form. Near the center, adjacent to the rear edge, the stock *i* has a cutter-post 2 provided with a substantially vertical guide-opening 3, in which is slidably mounted the shank 4 of the cutter. The shank 4, at the lower end has a laterally disposed cutter blade 5 and is formed at one side with a rack 6. In a suitable recess 7 within the post 2, is located a pinion 8 in mesh with the rack 6 and rigidly mounted upon the shaft 9, extending through a suitable transverse opening 10 of the post. A U-shaped yoke 11 is arranged with its sides 80 adjacent to the sides of the post and extending toward the shaft 9. A threaded pin 12 is located in a suitable threaded opening of the post, and has a head 13 by means of which it can be manually operated and adjacent to which it carries the yoke 11. The pin 12 has an annular groove 14, which is engaged by the extremity of a stud 15 mounted in a threaded opening of the yoke and holding the pin 12 in position with respect to the yoke. Thus, as the pin 12 is turned in one direction or the other by means of the head 13, the yoke is advanced toward or moved away from the shaft 9. By forcing the sides of the yoke, which are slightly recessed for the purpose, firmly against the shaft, the latter can be held against rotary movement and thereby the cutter which is controlled by the shaft can be locked in a plurality of positions. A collar 16, constituting a gage, 100 is mounted upon the portion of the shank 4 which projects above the post, and has a setscrew 17 by means of which it can be rigidly secured to the shank.

At one side, the plane stock has an annular handle support 18, rigidly mounted in position thereupon and carrying a handle 19, held in position by a screw stem 20, extending upwardly from the handle support and presenting a threaded extremity 21. The handle 19 is held in position upon the stem 20 by means of a counter-sunk nut 22,

mounted upon the threaded extremity 21 and arranged in a suitable recess at the top of the handle. At the opposite side of the plane stock a second handle support, 23 is 5 mounted in position by means of screws 24, extending upward through suitable openings in the sole plate. The handle support 23 has a substantially central projection 25, upon which is revolubly mounted a bevel gear 10 26, having an integral laterally disposed and flared socket 27, in which is carried a handle 28. A stem 29 is located in a suitable opening extending through the handle support 23, and the projection 25, and has a head 30 15 counter-sunk in a recess at the upper end of the handle 28, the stem 29 extending through a longitudinal opening in the latter. The recess which holds the head 30 is lined with a suitable sleeve 31. At one side the handle support 23 has a recess 32, in which is arranged a bevel gear 33 in mesh with the bevel gear 26 and rigidly mounted upon the shaft 9 which extends toward the handle support 23. The stock of the plane has an 20 extension 34, adjacent to the handle support 23, which serves as a bearing for the shaft 9 and as a stop or thrust block for the bevel gear 33, the back of which engages the extension 34. The stem 29 has a longitudinal 25 groove 35 which is engaged by a set-screw 36 carried by the handle support 23. The set-screw holds the stem 29 against rotary movement. The handle 28 which is arranged to be turned about the stem, seats 30 upon the projection 25 of the handle support. 35

To adjust the cutter of the plane, the head 13 is turned to release the yoke from the shaft 9, and the handle 28 is then turned in one direction or the other until the cutter 40 blade is projected the desired distance from the sole plate. It will be understood that as the handle 28 is turned the shaft 9 is turned by means of the bevel gears 26 and 33, and in consequence, the cutter is raised 45 or lowered by the operative engagement of the pinion 8 with the rack 6 formed upon the cutter shank 4. When the blade has been suitably adjusted, the head 13 is operated to jam the yoke against the shaft to 50 lock the latter in position. The set-screw 17 is then loosened and the gage-collar 16 slipped down the shank 4 until it engages the top of the post. The set-screw 17 is then tightened and the collar thereby secured 55 in position upon the shank. Should the cutter slip this would then no longer rest in position engaging the top of the post. I provide a central opening 37 in the stock or sole plate, substantially above the cutter 60 blade, to allow the operator to see the operation of the tool and through which opening the waste wood finds exit. As shown in Fig. 1, the cutter blade 5 can be seen through the opening 37, cutting the groove 38 in a plank 65. By means of the handle 28 the cutter

blade can be adjusted while the plane is being used, and even after the yoke has been tightened somewhat, for the construction of the regulating mechanism permits the application of considerable force to the adjustment of the blade. 70

Having thus described my invention, I claim as new and desire to secure by Letters Patent:

1. A plane, comprising a stock, a cutter 75 movable in the stock in a direction perpendicular to the face thereof, a movable handle, and gearing between the handle and cutter, said handle serving for the operation of the plane. 80

2. A plane, comprising a stock, a cutter carried by the stock and movable in a direction perpendicular to the face of said stock, said cutter having a toothed shank, a movable handle, mounted on the stock, a 85 pinion meshing with the teeth of the cutter shank, and means for operating the pinion from the movable handle.

3. A plane, comprising a stock, a cutter carried by the stock and movable in a direction perpendicular to the face of said stock, 90 said cutter having a toothed shank, a handle rigid with the stock, a handle mounted to turn upon the stock, a pinion meshing with the teeth of the cutter shank, and means for 95 operating the pinion upon turning the said handle.

4. A plane, comprising a stock, a cutter adjustably carried by said stock, means for locking said cutter in a plurality of positions, a gage in the form of a collar surrounding the shank of the cutter and secured thereto by a set screw, and a movable handle mounted upon said stock and controlling said cutter, said handle serving for 100 the manual operation of the plane. 105

5. In a plane, a stock, a cutter carried by the stock, a shaft operatively connected with the cutter for raising and lowering it, means for operating the shaft, and means for engaging the shaft to lock it in position. 110

6. A plane, comprising a stock having a cutter-post, a cutter movably mounted upon said cutter-post, means carried by said post for locking said cutter in a plurality of positions, an adjustable gage on the shank of the cutter above said post, a handle rigid with said stock, a revoluble handle mounted upon said stock, and means operatively connecting said revoluble handle and said cutter to permit the adjusting of said cutter by a movement of said revoluble handle, said handles serving for the manual operation of the plane. 115 120

7. A plane, comprising a stock having a 125 cutter-post, a cutter provided with a shank slidably carried by said post, said shank having a rack, means for locking said cutter in a plurality of positions, a revoluble handle having a gear and a shaft having a gear 130

in mesh with said first gear and a pinion in mesh with said rack.

8. A plane, comprising a stock having a cutter-post presenting a guide-opening, a cutter having a shank slidably mounted in said guide-opening and provided with a rack, a handle support, a revoluble handle pivotally mounted upon said handle support and having a gear, a shaft having a gear in mesh with said first gear and pinion in mesh with said rack, a member adjustably mounted upon said post and arranged to be forced against said shaft to lock said cutter in a plurality of positions, and a gage adjustably mounted upon said shank.
9. A plane, comprising a stock having a cutter-post presenting a guide-opening, a cutter having a shank slidably mounted in said guide-opening and provided with a rack, a handle support, a revoluble handle pivotally mounted upon said handle support and having a bevel gear, a shaft having a second bevel gear in mesh with said first bevel gear and a pinion in mesh with said rack, a yoke adjustably mounted upon said post and adapted to be projected against said shaft to lock said cutter in a plurality of positions, a gage adjustably carried by said shank, and a rigid handle mounted upon said stock.

10. A plane, comprising a stock having a cutter-post presenting a guide-opening, a cutter having a shank slidably mounted in said guide opening and provided with a rack, said stock having an opening therethrough adjacent to said cutter, a handle support, a bevel gear pivotally mounted upon said handle support and presenting a socket, a handle mounted in said socket, a shaft having a bevel gear in mesh with said first bevel gear, said stock having an extension engaging said second bevel gear and constituting a thrust block, said shaft having a pinion in mesh with said rack, said post having a threaded opening, a threaded pin mounted in said post, a yoke carried by said pin and adapted to move with said pin to engage said shaft to lock said cutter in a plurality of positions, a collar adjustably carried by said shank and constituting a gage, and a rigid handle carried by said stock, said handles serving for the manual operation of the plane.

In testimony whereof I have signed my name to this specification in the presence of two subscribing witnesses.
